Patented June 20, 1961

190,710

CHEESE SHREDDER OR SIMILAR ARTICLE

Anthony Jocius, Renehan Road, Round Lake, Ill.

Filed Jan. 31, 1961, Ser. No. 63,768

Term of patent 14 years

(Cl. D89—1)

FIG. 1 is a front elevational view of a cheese shredder embodying my new invention;

FIG. 2 is a side elevational view thereof as seen from the right hand side of FIG. 1;

FIG. 3 is a top plan view;

FIG. 4 is a side elevational view as seen from the left hand side of FIG. 1; and

FIG. 5 is a rear elevational view thereof.

I claim:

The ornamental design for a cheese shredder or similar article, substantially as shown.
